LABORATORY BALANCE

Fred W. Thompson, Denver, Colo.

Application February 3, 1941, Serial No. 377,156

7 Claims. (Cl. 265—54)

This invention relates to an analytical or laboratory balance. The usual analytical balance is provided with a hollow shaft or pedestal rising from the floor within the balance case for supporting the beam pivots and the beam lifting mechanism.

The principal object of this invention is to eliminate the post within the case and to support the beam and all related apparatus directly from the back wall of the case, such a construction results in greater accessibility to the balance pans and to a much more economical and facile method of manufacture.

Other objects of the invention are to provide a laboratory balance in which all the operating mechanism for lifting the beam will be accessible on the exterior of the case for repair, lubrication and adjustment; to provide guide bearings for the beam lifting mechanism which can be quickly and easily machined without requiring micro-metric boring and turning operations, which will be free from bearing looseness, and which can be easily adjusted to take up any wear or looseness which may occur in use.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a front view of a laboratory balance constructed in accordance with the principles of this invention;

Fig. 2 is a rear view thereof;

Fig. 3 is an enlarged vertical section therethrough, taken on the line 3—3, Fig. 1;

Fig. 4 is an enlarged fragmentary rear view with the cover plate removed to show the beam lifting rod;

Fig. 5 is a fragmentary horizontal section looking downward on the line 5—5, Fig. 3;

Fig. 6 is a similar section looking downward on the line 6—6, Fig. 3; and

Fig. 7 is an enlarged fragmentary section taken on the line 7—7, Fig. 4, illustrating the bearing for the lifting rod employed in the improved balance.

The principal feature of this invention is the improved construction for supporting and lifting the beam. The remainder of the balance may

have any standard construction. Typical standard parts of a balance are designated by numerals on the drawings as follows: beam 10, pans 11, pan bails 12, stirrups 13, knife edges 14, bearing posts 15, pivot studs 16, beam lifting yokes 17, rider shifting rod 18, agate bearings 30, plumb line 33, plumb indicating point 34, leveling legs 35, pointer 57, and indicating scale 58.

The balance illustrated is enclosed in a glass case consisting of metal frame 19, the sides of which contain glass panes 20 and the front of which is closed by a liftable glass door enclosed in a metallic door frame 21. The top is covered by a metal top plate 22, and the bottom is closed by means of a downwardly flanged floor plate 23.

The back of the case, however, is closed by two glass panes 55 which are separated vertically at the middle of the case by means of a tapered metallic supporting member 24 which extends as a unit from a middle leg 25, which supports the case at the rear, to the top plate 22. The member 24 is secured by means of cap screws 31 to the rear flange of the floor plate 23. It is also provided with a plumb post 32 from which the plumb line and plumb 33 depend over the indicating point 34 on the floor.

On the front of the member 24, below the beam 10, a pyramidal boss 26 is formed extending forwardly into the case. An angle bracket 27 is bolted to the boss 26 by means of suitable attachment bolts 28 and extends forwardly in the case beneath the beam 10. The two bearing posts 15 are attached to this angle bracket by means of suitable attachment screws 29 and extend fixedly upward therefrom in parallel relation, terminating in the usual agate bearings 30 for the knife edges 14. Thus, the beam and its operating mechanisms are supported in their proper position within the case without the use of any internal post or pedestal.

The beam lifting yokes 17 are secured to the forward extremity of a horizontal bracket member 36, preferably T-shaped in cross section, which is fixedly formed on, and at right angles to, a vertical lifting rod 37. The bracket member extends through an opening 56 in the supporting member. The lifting rod 37 extends vertically downward in a channel formed in the rear of the member 24. The rod 37 is formed with two bearing portions 38, one being positioned adjacent the top of the rod and one adjacent the bottom thereof. Opposite these portions of the rod, the channel at the rear of the member 24 is formed with two angularly-positioned, opposed, vertical

bearing surfaces 39, against which the bearing portion 38 of the rod rides.

A bearing plate 40 is secured across the channel opposite each bearing portion 38 of the rod. A U-shaped bearing piece 41 extends vertically between each plate 40 and the bearing portions 38 of the rod. The turned ends of the bearing pieces 41 rest in notches in the upper and lower edges of the plates 40. An adjusting screw 42 extends through each plate 40, by means of which its bearing piece 41 can be brought against the bearing portion of the rod to hold the latter against its two opposed surfaces 39 without side play and yet allowing free vertical movement thereof.

Thus, it can be seen that due to the fact that the bracket member 36 is formed at a fixed angle with the rod 37, the overhanging weight thereof is absorbed in the two three-line bearings on the rod 37, formed by the inclined channel sides and the bearing pieces 41.

An adjustable lift screw 43 is threaded into the lower extremity of the rod 37. The head of the screw 43 bears against an eccentric 44 secured on an eccentric shaft 45 extending forwardly across the case beneath the floor 23 and terminating in a knurled head 46. Thus, by rotating the head 46 in one direction, the rod 37 can be forced upwardly to cause the lifting yokes 17 to engage the studs 16 and lift the knife edges 14 from their bearing agates 33. The amount of lift should be exceedingly small, possibly two thousandths of an inch, so that very little swinging movement is imparted to the pans 11. The amount of lift can be easily adjusted by means of the adjustable lift screw 43. It is also essential that the lifting yokes 17 ascend in accurate vertical alignment with the studs 16 so that no sideward movement will be imparted to the beam. This vertical alignment is attained by means of a guide post 47 which extends downwardly through an enlarged opening 48 in the angle member 27. A contact screw 49 is threaded into each side of the angle member into contact with the post 47. By relative adjustment of these screws, the lifting yokes 17 can be accurately aligned with the studs 16. The horizontal bracket member 36 is perforated for the passage of the bearing posts and is entirely free therefrom.

The simplicity of the beam support and its lifting mechanism is apparent to anyone skilled in the art. All of the accurate drilling and reaming for the lifting rod and the accurate machining of the lifting rod has been entirely eliminated. The diameters of the rod are unimportant since it will always find a vertical bearing against the angular surfaces 38 and no drilling or reaming is necessary. Any looseness that may develop in the usual construction requires entire rebuilding. Any looseness which may develop in this construction can be quickly taken up by simply adjusting the screws 42. It is also desired to call attention to the fact that no floor space is occupied by any beam supporting mechanism. All supporting is accomplished from the rear wall of the case.

The lifting mechanism and its bearings are concealed and protected by means of a channel-shaped cover plate 50. The cover plate is formed with a hinge rod 51 extending across its channel at the top thereof which engages in a receiving notch 52 in a projecting boss 53 on the member 24. To place the cover plate in place, it is only necessary to engage the rod 51 in the slot 52 and then swing the cover plate inwardly. The sides

of the plate frictionally engage the two sides of the member 24 which are extended outwardly to enclose the lift rod and channel. The vertical edges of the cover plate 50 extend into vertical grooves 54 formed in the member 24 so as to form a concealed joint with the supporting member 24.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. In a laboratory balance, the combination with a case having side walls, a back wall, a top, and a floor, a supporting member at the mid-portion of said back wall; a bracket member extending forwardly into the case from said supporting member; means for supporting a scale beam from said bracket member; vertically aligned bearings on the rear of said supporting member; a lifting rod vertically slidable in said bearings; a beam lifting arm fixed to said lifting rod at its upper extremity and extending forwardly through said supporting member above said bracket member, and means on said lifting arm for lifting a beam from its bearings on said bracket member.

2. In a laboratory balance, the combination with a case having side walls, a back wall, a top, and a floor, a supporting member forming the mid-portion of said back wall; a bracket member extending forwardly into the case from said supporting member; means for supporting a scale beam from said bracket member; vertically aligned bearings on the rear of said supporting member; a lifting rod vertically slidable in said bearings; a beam lifting arm fixed to said lifting rod at its upper extremity and extending forwardly through said supporting member above said bracket member, and means on said lifting arm for lifting a beam from its bearings on said bracket member; each of said vertically aligned bearings comprising, a channel open on the rear of said supporting member, oppositely inclined vertical side walls in said channel against which said rod rests, and means for holding said rod against said inclined side walls.

3. In a laboratory balance, the combination with a case having side walls, a back wall, a top, and a floor, a supporting member forming the mid-portion of said back wall; a bracket member extending forwardly into the case from said supporting member; means for supporting a scale beam from said bracket member; vertically aligned bearings on the rear of said supporting member; a lifting rod vertically slidable in said bearings; a beam lifting arm fixed to said lifting rod at its upper extremity and extending forwardly through said supporting member above said bracket member, means on said lifting arm for lifting a beam from its bearings on said bracket member; each of said vertically aligned bearings comprising, a channel open on the rear of said supporting member, oppositely inclined vertical side walls in said channel against which said rod rests; a cover member extending across each channel, and an adjusting screw in each cover member for urging said rod against said inclined side walls.

4. In a laboratory balance, the combination with a case having side walls, a back wall, a top,

and a floor, a supporting member forming the mid-portion of said back wall; a bracket member extending forwardly into the case from said supporting member; means for supporting a scale beam from said bracket member; vertically aligned bearings on the rear of said supporting member; a lifting rod vertically slideable in said bearings; a beam lifting arm fixed to said lifting rod at its upper extremity and extending forwardly through said supporting member above said bracket member, means on said lifting arm for lifting a beam from its bearings on said bracket member; each of said vertically aligned bearings comprising, a channel open on the rear of said supporting member, oppositely inclined vertical side walls in said channel against which said rod rests; a bearing strap extending vertically against said rod opposite said inclined side walls, and means for holding said bearing strap against said rod.

5. In a laboratory balance, the combination with a case having side walls, a back wall, a top and a floor of a supporting member forming the mid-portion of said back wall; a bracket member extending forwardly into the case from said supporting member; and means for supporting a scale beam from said bracket member, vertically aligned bearings on the rear of said supporting member; a lifting rod vertically slideable in said bearings; a beam lifting arm fixed to said lifting rod at its upper extremity and extending forwardly of said supporting member above said bracket member, and means on said lifting arm for lifting a beam from its bearings on said bracket member, each of said vertically aligned bearings comprising, a channel open on the rear of said supporting member, oppositely inclined, vertical side walls in said channel against which said rod rests, a bearing strap extending vertically against said rod opposite said inclined side walls, means for holding said bear-

ing strap against said rod, said rod and its bearing channels being exposed on the rear of said supporting member on the exterior of said case, and a removable cover plate concealing the same.

- 5 6. Means for supporting the bearings of a laboratory scale beam and means for lifting said beam from its bearings comprising: a vertical supporting member; a bracket extending from said supporting member; bearing means carried by said bracket for said scale beam; an inverted, L-shaped lifting member having a horizontal, upper leg and a vertical lifting rod fixedly joined at right angles to each other, the lifting rod extending between said beam and said bracket member and carrying means for lifting the beam, the rod extending vertically along one face of the supporting member in a receiving channel therein; oppositely inclined side walls in said channel against which said rod bears along vertical lines; means for holding said rod against said side walls; and means for lifting said rod.
- 10 7. Means for supporting the bearings of a laboratory scale beam and means for lifting said beam from its bearings comprising: a vertical supporting member; a bracket extending from said supporting member; bearing means carried by said bracket for said scale beam; an inverted, L-shaped lifting member having a horizontal, upper leg and a vertical lifting rod fixedly joined at right angles to each other, the lifting rod extending between said beam and said bracket member and carrying means for lifting the beam, the rod extending vertically along one face of the supporting member in a receiving channel
- 15 25 30 35 40 therein; oppositely inclined side walls in said channel against which said rod bears along vertical lines; a cover plate extending across said channel; an adjusting screw in said cover plate for urging said rod against its inclined side walls; and means for lifting said rod.
